(57) **CLAIM**

The ornamental design for a cone cap, as shown and described.

DESCRIPTION

FIG. 1 is a perspective view of the cone cap showing my new design;

FIG. 2 is an enlarged front elevational view thereof;

FIG. 3 is an enlarged top plan view thereof, the bottom plan view being a mirror image thereof;

FIG. 4 is an enlarged rear elevational view thereof;

FIG. 5 is an enlarged side elevational view of the right side thereof, the side elevational view of the left side being a mirror image thereof; and,

FIG. 6 is a sectional view taken along the line 6—6 of FIG. 2.
